UNITED STATES PATENT OFFICE.

GEORGE LORING, OF BAR HARBOR, MAINE.

DESIGN FOR A CHAIR.

SPECIFICATION forming part of Design No. 31,875, dated November 21, 1899.

Application filed October 26, 1899. Serial No. 734,893. Term of patent 7 years.

To all whom it may concern:

Be it known that I, GEORGE LORING, a citizen of the United States, residing at Bar Harbor, in the county of Hancock and State 5 of Maine, have invented and produced a new and original Design for a Chair, of which the following is a specification.

The invention relates to a new and original design for a chair; and it has for its object 10 to provide a design of this character which will be both ornamental and useful.

The leading feature of the design resides in a chair having massive ornamental corner-posts and provided with an ornamental front 15 round or bar and having a back arranged between the rear corner-posts and provided with an ornamental top bar.

The figure of the drawing is a perspective view of a chair showing my new and original 20 design.

Referring to the drawing, 1 and 2 designate front and rear posts, which form the legs of the chair, and these posts, which are round, are massive in appearance, and the rear ones, 25 which are extended at opposite sides of the back 3 of the chair, are provided at intervals with ornamental rings and have smooth panel portions 5 between the series of rings. The uppermost series of rings are tapered, 30 and the upper ends of the rear posts terminate in balls, which are connected with the adjacent panel portions 5 by the tapering

portions formed by the uppermost series of rings. The front posts 1 have smooth round portions and extend above the seat 8, and 35 they are provided with ornamental rings 1^a, located about midway between the seat 8 and the rockers 7. The lower ends of the front posts are connected with the rockers 7, and their upper portions are provided with concentric grooves or rings 10 and 11, located beneath the arms 9. The portions 12 between the grooves or rings 10 and 11 present a rounded appearance. The front round or bar is massive in appearance, and it is provided 40 at intervals with concentric rings 13 and has tapered portions 14 between the rings.

The back 3, which is arranged between the rear posts, is provided at its top with an ornamental cross-bar 15, arranged adjacent 45 to the uppermost panels 5 and having a curved or scalloped upper edge 16, forming a central tapering projection 17.

What is claimed is—

The design for a chair, as herein shown and 50 described.

In testimony that I claim the foregoing as my own I have hereto affixed my signature in the presence of two witnesses.

GEORGE LORING.
